and one-half to Gladys Tucker, Magnolia, N. J.

Application February 8, 1938, Serial No. 189,302

4 Claims. (Cl. 16—135)

This invention relates to hinges, and more particularly to hinges of the concealed type, the present invention being particularly suitable for use in mounting doors on automobile bodies or the like.

In my copending application Serial No. 184,356, filed January 11, 1938, I have disclosed a concealed hinge comprising a stationary bracket member provided with a spherical socket or bearing in which is mounted a ball formed on the movable element of the hinge. The stationary element of the hinge is concealed within the door frame and the movable element thereof is secured to the door and is arranged to be received within a well or recess in the bracket member when the door is in closed position. In certain cases it has been found advantageous to provide additional bearing support for the movable element of the hinge which carries the door, and the primary object of my present invention is to provide an improved hinge of the concealed type having a greater bearing support than that disclosed in my aforesaid copending application.

More specifically, it is an object of my present invention to provide an improved hinge as aforesaid which has sufficient bearing support for the movable element thereof to satisfactorily carry even a very heavy door without permitting it to sag in the frame.

Another object of my present invention is to provide an improved hinge of the type set forth which will stand up under long and continued use and which will at all times maintain the door properly fitted in its frame.

Still another object of my present invention is to provide an improved hinge, as above described, which can be attached in place easily and to which the door can be just as easily secured, or from which the door can be easily removed.

A further object of my present invention is to provide an improved hinge of the concealed type which is simple, yet durable, in construction, which is highly efficient in use, which readily lends itself to the requirements of economical quantity manufacture, and which is inexpensive in cost.

In accordance with my present invention, I form the hinge similarly to that disclosed in my aforesaid application, that is, with a stationary supporting bracket having a socket formed at least partially on a sphere and which receives a correspondingly formed element on the swingable member of the hinge, the socket acting as one bearing for the swingable member. In addition,

I provide a pintle which extends through the socket and the element received therein, so that the pintle, which is coaxial with the spherical portion of the socket, acts as an additional bearing for the swingable member. There is thus provided a pair of concentric, radially spaced, bearings which solidly support the swingable member of the hinge.

The novel features that I consider characteristic of my invention are set forth with particularity in the appended claims. The invention itself, however, both as to its organization and method of operation, together with additional objects and advantages thereof, will best be understood from the following description of several embodiments thereof, when read in connection with the accompanying drawing, in which

Figure 1 is a bottom plan view of one form of my present invention,

Figure 2 is a central sectional view thereof, 20

Figure 3 is a bottom plan view of a slightly different form of my present invention, and

Figure 4 is a central sectional view of the latter form of my invention.

Referring more in detail to the drawing, and particularly to Figs. 1 and 2, there is shown a hinge comprising a bracket member 1 formed with an offset portion 3 which terminates at one end in a partially spherical ball socket 5, the entire structure being an integral unit which may be formed, for example, by drawing the material of the bracket between suitable dies. The offset portion 3 provides an elongated well or recess 7 in which is received an L-shaped member 9 having a ball 11 formed integrally thereon at one end of one of the arms of the L. The ball 11 is mounted in the socket 5 and the edge portion 5a thereof is forced around the ball 11 whereupon the completed socket 5 acts as a bearing for the ball 11. A pintle 13 having its ends 15 headed over against the socket 5 extends through the socket 5 and the ball 11 coaxially with the socket 5 and in a direction normal to the plane in which the swingable member 9 moves into and out of the recess 7, as shown by the solid and the dot-and-dash lines in Fig. 2. Thus, the pintle 13 acts as an inner bearing member for the swingable element 9 and the socket 5 acts as an outer bearing member therefor. Together, therefore, the two bearing means 5 and 13 provide an exceptionally strong bearing support for the element 9.

The offset portion 3 of the bracket member is inserted into a suitable recess in the door frame (not shown) and the bracket member 1 is secured 55

to the frame by means of screws passing through elongated openings 17 in the bracket member, the openings 17 being elongated to permit adjustment of the hinge to its desired position. 5 Thereafter, the threaded free end 19 of the swinging member 9 is inserted into a suitable opening 21 in a door 23 which is to be mounted in the door frame, and a pair of cooperating nuts 25 and lock washers 27 are tightened up, first rather 10 loosely until the door is fitted to the frame, and then very tightly to hold the door firmly in position. Usually, a pair of hinges is used for each door, and once the door has been thus fitted, it 15 will always remain in proper fitting relation with the frame.

The modification of my invention shown in Figs. 3 and 4 is quite similar to that previously described. In this modification, however, the socket 5 has the shape of a sphere on which two 20 diametrically opposed flat sides 5b have been formed, as by pressing these sides toward each other in parallel relation, and the ball 11 is similarly formed to provide the flat sides 11a which bear against the flat sides 5b. Also, the flattened "ball" 11 is centrally bored on a diameter greater than that of the pintle 13 and a bronze or other suitable bushing 29 is placed within the bore for the reception of the pintle 13. As in the 25 modification of Figs. 1 and 2, that shown in Figs. 3 and 4 provides a double bearing support for the swinging element 9, the two bearing means 5 and 13 being concentric, and in radially spaced relation, and the socket 5 constituting an integral part of the stationary bracket member. 30

Although I have shown and described but two embodiments of my present invention, it will be obvious to those skilled in the art that many other modifications thereof are possible. I therefore desire that my invention shall not be limited except insofar as is made necessary by the prior art and by the spirit of the appended claims.

I claim as my invention:

45 1. A hinge comprising a relatively stationary bracket member adapted to be secured to one of a pair of cooperating members constituting a door and frame, said bracket member having an offset portion formed with a bearing socket con-

stituted by at least a partial sphere, a relatively movable member adapted to be secured to the other of said pair of cooperating members and having an integral element thereon of the same shape as said socket, said element being mounted in said socket to permit swinging movement of said movable member relative to said stationary member, and a pintle extending through said socket and said element, said pintle having contact with said element throughout substantially the entire length thereof at all times and constituting an additional bearing for said element. 5

2. A hinge comprising, in combination, a relatively stationary bracket member adapted to be secured to a door frame, said member being 10 formed with an elongated recessed portion having a socket at one end thereof formed in the shape of at least a partial sphere and constituting a bearing, a relatively movable member adapted to be secured to a door and having an element thereon formed in a shape similar to that of said socket, said element being mounted in said socket for swinging movement of said movable member into and out of said recessed portion, and a pintle extending through said 15 socket and said element, said pintle constituting an additional bearing for said element and being coaxial with said sphere. 25

3. A hinge according to claim 2 characterized in that said pintle extends through said 30 sphere in a direction normal to the plane in which said movable member swings.

4. A hinge comprising, in combination, a relatively stationary bracket member adapted to be secured to a door frame, said member being 35 formed with an elongated recessed portion terminating at one end in a spherical socket constituting a bearing, a relatively movable member adapted to be secured to a door at one of its ends and terminating in a ball at its other 40 end, said ball being mounted in said socket for swinging movement of said movable member into and out of said recessed portion, and a pintle extending through said socket and said ball, said 45 pintle constituting an additional bearing for said movable member and being coaxial with said ball and socket.

MORTON TUCKER.
